UNITED STATES PATENT OFFICE.

JOHN H. BARR, OF SYRACUSE, NEW YORK, ASSIGNOR TO THE SMITH PREMIER TYPE-WRITER COMPANY, OF SYRACUSE, NEW YORK, A CORPORATION OF NEW YORK.

TYPE-WRITING MACHINE.

933,048.

Specification of Letters Patent.

Patented Sept. 7, 1909.

Application filed February 21, 1907. Serial No. 358,591.

To all whom it may concern:

Be it known that I, JOHN H. BARR, citizen of the United States, and resident of Syracuse, in the county of Onondaga and State of New York, have invented certain new and useful Improvements in Type-Writing Machines, of which the following is a specification.

My invention relates especially to the paper feeding mechanism of typewriting machines, and has for its main object to provide improved devices for controlling the paper or work sheets to be written on, and which devices are particularly adapted to 15 the class of work commonly called "condensed record" work.

To the above and other ends, the invention consists in the features of construction, combinations of devices and arrangements 20 of parts hereinafter described at length and particularly pointed out in the claims.

My invention is illustrated as applied to a platen carrier like that employed on the Smith Premier typewriting machine, but 25 the nature of my improvements is such that they may be readily adapted to other forms of writing machines.

In carrying out my invention in the present instance I arrange a pair of parallel 30 links on the rear rod of the platen carrier, said links carrying a feed roller which may be termed a secondary or supplementary feed roller in contradistinction from the usual main feed rollers and also from the 35 usual margin feed rollers of the machine. This secondary feed roller extends lengthwise of the platen and is arranged above or in advance of the main feed roller and between the platen and the usual paper table. 40 Springs tend constantly to press this supplementary feed roller into engagement with the platen or the paper thereon. The paper table is inclined upwardly away from the platen at the introductory side thereof and 45 forms with the platen a sort of pocket-like opening comparatively wide at the top or mouth and tapering toward the lower end. The secondary feed roller is arranged in the mouth of this pocket-like opening in such a 50 way as to provide two passage-ways for the paper or work sheets, one of said passage-ways being between the platen and the secondary feed roller and the other between the said feed roller and the paper table. The

main feed roller, of course, is arranged below the paper table so as to receive the work sheets as they pass downwardly out of the pocket-like opening between said paper table and the platen.

In doing condensed record work to which my improvements are especially adapted the record sheet is preferably introduced into the machine between the platen and the secondary feed roller by which it is initially controlled, thence passing downwardly into the control of the main paper feed roller, while the bill sheet and the carbon inlay are introduced into the machine over the paper table in the usual way and are guided downwardly through the passage-way between said paper table and the secondary feed roller, thence passing into the control of the main paper feed roller. After passing into control of the main feed roller the sheets are subsequently fed and guided through the machine in the usual way. The main feed roller is controlled by hand operated releasing means and when this means is operated the bill sheet and the carbon inlay are freed so that they may be withdrawn from the machine and a new bill sheet and carbon inlay inserted. During this withdrawal of one bill sheet and the substitution of another the record sheet remains in the machine under the control of the platen and the secondary feed roller.

The special advantages of my invention will be explained at length later on.

In the accompanying drawings, Figure 1 is a rear elevation of a platen and platen carrier of a Smith Premier machine to which my invention is shown as applied, parts being omitted and other parts broken away for the sake of clearness. Fig. 2 is a transverse sectional view of the platen, the platen carriage and the supports of said carriage. Fig. 3 is a sectional view of the platen and platen carrier corresponding to Fig. 2 and showing various parts as they appear during paper feeding operations. Fig. 4 is an end elevation showing the platen carrier and platen as they appear when viewed from the left-hand end and with the finger wheel sectioned away, the parts being shown as they appear when the main paper feed roller is released and locked in the released position. Fig. 5 is an enlarged fragmentary longitudinal sectional view taken

centrally of the secondary feed roller and showing the construction and mounting thereof.

In the drawings 1 designates the top plate 5 on which are supported oppositely grooved track-ways 2 and 3 which receive anti-friction balls 4, the latter also coöperating with the grooved front and rear bars 5 and 6 respectively of a carriage truck, the latter also 10 comprising end or side bars 7 only one of which is shown. A rotary platen 8 is secured to a platen axle 9 which is supported on the side bars 7 of the carriage truck. The platen axle is journaled on the end plates 10 of a platen frame or carrier, the latter also comprising front and rear bars numbered respectively 11 and 12. Studs 13 project laterally from the side plates 10 of the platen frame and are engaged by hooked 15 links 14 pivoted at 15 to the side bars 7 of the truck. The truck and the platen frame or carrier constitute a platen carriage. It will be understood that the platen is adapted to rotate on the platen frame, being controlled in such movements by the usual line spacing devices (not shown), or by the finger wheels 16 fixed on the ends of the axle 9. It will further be understood that the platen and platen frame are adapted to be rocked 20 on the carriage truck to expose the writing, the rocking movements being conveniently controlled by a finger piece 17 fixed to the front bar 11 of the platen carrier. Links 18 are pivoted to and depend from the rear bar or rod 12 of the platen carrier, said links carrying a rod or shaft 19 in which is mounted a paper feed roller 20 hereinafter termed the main feed roller. This paper feed roller extends lengthwise of the platen 25 and is shown in the present instance as a single roller though obviously it may be divided to provide a plurality of separate rollers. The roller 20 is pressed into engagement with the platen or with the paper thereon by leaf springs 21 which are secured by nuts 22 to threaded pins 23 projecting rearwardly from standards 24 rising from and fixed to the rear bar 12 at each end portion thereof. The lower or free ends of the 30 springs 21 coöperate with sleeves 25 arranged on the rod 19, one near each end between an end of the feed roll 20 and the neighboring link 18. The paper table 26 is suitably secured to the standards 24 and is 35 inclined upwardly at the rear or introductory side of the platen and above the main feed roller 20. A rod or shaft 27 is carried by the links 18 below the rod 19 which supports the main feed roller, said rod 27 being 40 of smaller diameter than the rod 19 and serving as a pivotal support for a paper plate 28, the latter extending forwardly at the under side of the platen and its free end portion being spring-pressed toward the 45 platen by the rear end portions of paper

guiding fingers 29, the latter being suitably secured to supporting arms 30 rising from the front frame bar 11 and slidably mounted thereon.

The platen and its mounting and the paper feeding devices thus far described do not differ essentially from those found on the No. 4 Smith Premier machine and it is not deemed necessary to describe them at greater length.

A hand-operated releasing lever 31 is suitably secured to the left end of the rod or shaft 19 in a fixed relation with said rod or shaft, said lever being provided with a tail 32. When the hand lever 31 is swung 75 forward its tail 32 fulcrums in the usual way on the platen frame near the rear left-hand corner thereof, the movement of the lever being effective to release the main feed roller 20 or move it away from the platen to inoperative position as shown in Fig. 4. From an inspection of this figure it will be noted that the releasing operation also serves to release the paper plate 28 and the paper fingers 29, the pivotal movement of the paper plate on the rod 27 being limited in one direction so that the plate is effective to move off the paper fingers.

I prefer also to employ means for locking the main feed roller, the paper plate and the paper fingers in released position and any convenient means may be made use of for this purpose. That shown in the drawings comprises a latch 33 of sheet metal pivoted on a headed shouldered screw 34 which is 80 screwed into the release lever 31. The rear end of the latch is bent laterally to provide a finger piece 35 and the forward end of the latch is formed with a longitudinal slot 36 having a downward extension 37 at its rear 85 end. Engaging this slot is a headed screw 38 which projects inwardly from the inner face of the left-hand side plate 10 of the platen frame. The normal relation between the screw 38 and the latch 33 is shown in 90 Fig. 2 where it will be noted the screw 38 is engaged with the forward end of the slot 36. When the latch 33 is employed and it is desired to release the paper feeding and controlling devices and lock them in released 95 position, this may be accomplished by pressing forward and downward against the finger piece 35 of the latch, causing the releasing lever 31 to swing forward to release the paper feeding and controlling devices and 100 causing the latch 33 to move forward bodily and to turn slightly on its pivot 34. The result is that the lower edge of the slot 36 bears against the shank of the screw 38 as the latch moves forward, and when the extension 37 of the slot 36 reaches the screw 38 105 the latch receives a slight upward pivotal movement so that the extension 37 engages the pin, locking the parts in the position shown in Fig. 4. The latching or locking 110

device described is not my invention, nor is it claimed *per se* by me, and it is not deemed necessary to explain its operation in greater detail at this place.

5 Referring now to the novel auxiliary or secondary feed roller of my invention, links 39 extend upwardly from the rear bar 12 of the platen carrier outside the links 18, said links 39 being formed at their lower ends 10 with hubs 40 which are perforated to receive the bar 12, the latter constituting a pivotal support for said links. As shown in Fig. 1 the hub 40 of the link 39 at the left in said figure is confined between the contiguous 15 link 18 and a boss 41 integral with the neighboring side plate 10 of the platen frame, and in which boss the end of the rear bar 12 of said platen frame is seated. The construction is such that while the left-hand 20 link 39 may turn freely on the bar 12 it is prevented from moving endwise of said rod. The upper end portions of the links 39 support, and are connected by, a rod 42 which is secured in place by headed screws 43, the 25 latter being received in threaded openings in the ends of the rod 42, as shown in Fig. 5, the end portions of the rod 42 passing through perforations in the links 39. Mounted to turn on the rod 42 is a secondary feed 30 roller comprising an inner metal core 44 and an external sheath 45 of rubber or the like. Sleeves 46 may be arranged on the rod 42 between the ends of the core 44 and the links 39. The secondary feed roller, as 35 shown in Figs. 2, 3 and 4, is arranged between the platen and the paper table and cooperates directly with the platen or the paper thereon, being constantly pressed toward the platen by U-shaped springs 47 which 40 may be mounted horizontally on the threaded pins 23 between the leaf springs 21 and the backs of the standards 24. The rear portions of the springs 47 are extended laterally outward or toward the end bars of 45 the platen carrier, as shown in Fig. 1, the extensions being designated by the numerals 48. The end portions of the spring extensions 48 are perforated to engage the reduced ends 49 of studs 50 projecting rearwardly from the links 39, the construction 50 being such that the springs 47 press the links forwardly and through them transmit pressure to the secondary feed roller. This secondary feed roller, it will be understood, 55 may have a pivotal motion about the rear bar 12 of the platen frame but is held from movement lengthwise of the platen frame by reason of the fact that one of the links 39 is held from moving lengthwise of the 60 rear bar of the platen frame as has been described. The secondary feed roller as shown extends longitudinally of the platen, substantially through its working length, but it will be apparent that said secondary feed roller may be shortened or lengthened 65

at pleasure, and may be made in one or more sections.

In making use of my invention for condensed record work, the record sheet, designated in the drawings by the reference character *a*, may be introduced into the machine between the platen and the secondary feed roller and fed around with the platen between the latter and the secondary and main paper feed rollers and the other paper feed- 70 ing and controlling devices as illustrated in Fig. 3. The bill sheet and the carbon inlay, designated respectively by the reference characters *b* and *c*, may be introduced into the machine over the paper table 26 and between it and the secondary feed roller, and thence guided downward between the paper table and the platen, passing into the control of the platen and the main feed roller and thence forward and upward out of the machine in the usual way. When the printing instrumentalities are actuated after the introduction of the bill and record sheets and the carbon inlay in the manner described, the type impressions will be made through 75 the usual inking ribbon on the bill sheet *b* and will be reproduced through the carbon inlay *c* on the record sheet *a*. After the writing of the bill sheet has been completed the platen may be line spaced one or more 80 times to provide for a sufficient space on the record sheet between the last item or line of the bill just written and the first line or item of the next succeeding bill to be reproduced on the record sheet. The completed bill sheet may then be withdrawn. To effect this withdrawal the finger piece 35 of the latch 33 may be pressed or pulled forwardly as 85 has been described until the latch is locked and the main paper feed roller 20, paper plate 28 and the paper fingers 29 are released and held released as illustrated in Fig. 4. From an inspection of this figure it will be noted that the operation of the release devices does not affect the secondary feed 90 roller which remains in co-operation with the platen to hold and control the record sheet *a*. The bill sheet and carbon inlay, however, are entirely freed from control of the paper feeding devices by the releasing operation 95 and may be readily withdrawn and a new bill sheet and carbon inlay may be introduced into the machine and arranged in position for writing the first line thereon, after which the release latch 33 may be unlocked 100 and the released parts allowed to return to normal position. The writing of the new bill may then be proceeded with, said writing being duplicated on the record sheet *a* close to the reproduction of the preceding 105 bill. Condensed record work for typewriting machines has come to be so well known in the art that it is not thought necessary to enter into greater detail concerning the various stages of the operation, it being un- 110

derstood that as each bill sheet is introduced into the machine the first or date line thereon is brought to the printing line and that the bill sheet is guided in such movement by the usual paper feeding and directing devices.

While I have described the carbon inlay *c* as being introduced into the machine with the bill sheet *b*, it will of course be understood that the carbon inlay may be introduced with the record sheet *a* between the platen and the secondary feed roller and may be held in the machine when the bill sheet is withdrawn. It will be also understood that various other changes in procedure may be made at the pleasure of the operator.

It will be apparent that while my invention in itself comprises few parts and is comparatively simple in construction, yet, nevertheless, by its use condensed record work may be greatly expedited and the comparatively elaborate and complicated means frequently employed for doing this class of work may be dispensed with. No dial or stop mechanism is used and it is not necessary to turn the platen back and forth when a bill sheet is to be withdrawn and a new one inserted. Moreover, no so-called terminal paper controlling devices or feed rollers arranged at the sides of the main paper controlling device or feed roller are employed in the present instance, and consequently it is not necessary as heretofore to use a record sheet and a bill sheet different in width; nor is it necessary to employ separate side guides for the record and work sheets; nor to exercise great care in introducing the bill sheet at the proper place longitudinally of the platen so that it will not when fed into the machine come within the control of the terminal feed rollers or devices; nor is it necessary to employ pairs of directly co-operating feed rollers. Furthermore, the carbon is not so liable to offset or come off on the record sheet when a secondary feed roller, co-operating with the record sheet substantially throughout its width, is employed as it is when short terminal feed rollers co-operate with the side portions only of the carbon sheet or inlay. In the present instance the record sheet and the bill sheet may be equal in width and may be fed into the machine so that their side edges lie in the same planes.

In the present case a single secondary feed roller or paper controlling device is employed which is arranged to co-operate directly with the platen or the paper thereon at the introductory side of the platen in advance of the main feed roller, said secondary paper controlling device or feed roller extending along the platen and being arranged parallel with the main paper feed roller and so that a plane transverse of the platen will cut both feed rollers. The sec-

ondary feed roller is placed between the platen and the paper guide 26 which is commonly termed the paper table, and said secondary feed roller is so located with respect to the platen and the paper guide 26 as to provide two passage-ways for the introduction of paper or work sheets. One of these passage-ways is between the secondary feed roller and the platen and the work sheet introduced into this passage-way is fed initially by the co-operation between said feed roller and the platen. The other passage-way is between the secondary feed roller and the paper guide or table 26 and the work sheets introduced into this passage-way are passed downward over the paper table without their being affected by the secondary feed roller. The inclined paper table 26 forms with the platen a sort of V-shaped opening or pocket which widens gradually from the bottom toward the top and in the mouth of which the secondary feed roller is located. The bottom of the pocket forms a comparatively narrow opening toward which the work sheets introduced at opposite sides of the secondary feed roller gradually converge and through which they pass downwardly into the control of the main feed roller which in the present instance is located below the paper table. The paper table or plate-like paper guide 26, it will be noted, though bent slightly at its top and bottom edges away from the platen, lies for the most part in a plane which may be termed the general plane of the paper table or paper guide, and it will be seen that by arranging the secondary and main feed rollers at opposite sides, or substantially at opposite sides of the general plane of the paper table, the secondary feed roller being at the front and the main feed roller for the most part behind this general plane, I am enabled to obtain desirable results. Furthermore, the construction is such that certain of the sheets may pass to one side of the secondary feed roller and between it and the platen so that said roller co-acts with the sheet or sheets in question to clamp them to the platen and effect a feed thereof when desired, whereas another sheet or other sheets pass on the opposite side of said roller and are out of the control thereof and may be introduced into or removed from the machine without disturbing said roller or the sheets or sheets controlled thereby.

Various changes may be made in the construction without departing from the spirit and scope of my invention.

What I claim as new and desire to secure by Letters Patent, is:—

1. In a typewriting machine and in a condensed record mechanism, the combination with a rotary platen, of a main feed roller; and a continuous secondary feed roller arranged lengthwise of the platen, said feed

- rollers being parallel with each other and both coöperating directly with the platen or the paper thereon, the main feed roller being arranged to coöperate with both the record sheet and the bill sheet and the secondary feed roller being arranged to coöperate with one only of said record and bill sheets and operating to feed the one sheet independently of the other sheet.
2. In a typewriting machine and in a condensed record mechanism, the combination with a rotary platen, of a main feed roller normally in spring-pressed engagement with the platen; a continuous secondary feed roller normally in spring-pressed engagement with the platen, said feed rollers being arranged lengthwise of the platen and parallel with each other, the main feed roller being arranged to coöperate with both the record sheet and bill sheet and the secondary feed roller being arranged to coöperate with one only of said bill and record sheets and operating to feed the one sheet independently of the other sheet; and means for releasing the main feed roller.
3. In a typewriting machine, the combination of a rotary platen, a paper feed roller extending continuously along the platen and arranged so that work sheets may be introduced at opposite sides of it into the machine, said work sheets being adapted to be advanced independently, said paper feed roller coöperating with only one of said work sheets to advance it, and separate means for advancing the other one of said work sheets.
4. In a typewriting machine, the combination with a rotary platen, of a paper table lying behind said platen and inclining upwardly and rearwardly therefrom so as to form with said platen an opening or pocket, the width of which increases from the bottom upwardly; a feed roller arranged at the mouth of said pocket and so that a passage is afforded for paper at each side of said feed roller; and a second feed roller arranged below the first mentioned feed roller, both said feed rollers coöperating directly with the platen and each operating independently of the other to feed paper.
5. In a typewriting machine, the combination of a platen frame or carrier; a platen rotatable thereon; parallel links pivoted on said platen frame and carrying the main feed roller, springs pressing said main feed roller constantly toward the platen; other parallel links pivoted to said platen frame and carrying a secondary feed roller; springs constantly pressing said feed roller toward the platen; and a paper guide or table mounted on standards rising from said platen frame, said standards each carrying one of the main feed roller springs and one of the supplementary feed roller springs.
6. In a typewriting machine, the combination of a platen frame or carrier; a platen rotatable thereon; downwardly extending parallel links pivoted on said platen frame and carrying a main feed roller; springs pressing said main feed roller constantly toward the platen; upwardly extending parallel links pivoted to said platen frame and carrying a secondary feed roller; springs constantly pressing said secondary feed roller toward the platen; a releasing rod carried by said first named links; and ha. l. 75 actuated means for operating said rod to release said main feed roller.

Signed at Syracuse, in the county of Onondaga, and State of New York this 18th day of February A. D. 1907.
